ABSTRACT

A step stool having a platform having a length at least 1.5 times a length of a first step. The platform rotatably attached to a first front leg and a second front leg above the first step. The first step having a perimeter having a first side which extends down from a top of the first step. The first step having a first boss that extends outward from the first side through which a first fastener extends to attach the first front leg to the first step. The first step having a rib which extends outwards from the first side adjacent the first boss and in alignment with the first front leg when the first and second front legs and first and second rear legs are in an open position where they form a generally upside down V shape. The rib providing support to the first front leg when a cantilever type force is applied to the stepladder. A method for using a step stool.

FIG.1

FIG. 9

1

STEP STOOL WITH RIB, AND METHOD

CROSS-REFERENCE TO RELATED APPLICATIONS

This is a nonprovisional of U.S. provisional patent application Ser. No. 62/521,827 filed Jun. 19, 2017, incorporated by reference herein. This application incorporates by reference U.S. design patent application Ser. No. 29/608,055 filed Jun. 19, 2017.

FIELD OF THE INVENTION

The present invention is related to a step stool with a platform that has a rib extending from the platform to support a leg of the step stool against a cantilever type load. (As used herein, references to the "present invention" or "invention" relate to exemplary embodiments and not necessarily to every embodiment encompassed by the appended claims.) More specifically, the present invention is related to a step stool with a platform that has a rib extending from the platform to support a leg of the step stool against a cantilever type load, where the rib extends from a boss on the outside of the platform in lines with a leg which the rib is supporting.

BACKGROUND OF THE INVENTION

This section is intended to introduce the reader to various aspects of the art that may be related to various aspects of the present invention. The following discussion is intended to provide information to facilitate a better understanding of the present invention. Accordingly, it should be understood that statements in the following discussion are to be read in this light, and not as admissions of prior art.

Step stools are commonly used to access somewhat higher locations relatively often. Since they are used often, it is desirable for them to be as lightweight and a strong as possible. Typically step stools have one or two steps with a platform. The platform allows the user more freedom to securely move around while standing on the platform in accessing a desired higher location, with the step or steps providing access to the platform. It is important for safety reasons of the user to make a step stool as resistant as reasonably possible to various types of loads on the legs of the step stool so the legs do not bend or fail.

BRIEF SUMMARY OF THE INVENTION

The present invention pertains to a step stool. The step stool comprises a first front leg. The step stool comprises a second front leg in parallel and spaced relation with the first front leg. The step stool comprises a first step having a length rotatably attached to the first front leg and the second front leg, a top and a perimeter about the top. The perimeter having a first side which extends down from the top. The first step having a first boss that extends outward from the first side through which a first fastener extends to attach the first front leg to the platform. The first step having a rib which extends outwards from the first side adjacent the first boss and in alignment with the first front leg when the first and second front legs and first and second rear legs are in an open position where they form a generally upside down V shape. The rib providing support to the first front leg when a cantilever type force is applied to the step stool. The step stool comprises a first rear leg hingedly attached to the first front leg. The step stool comprises a second rear leg hingedly attached to the second front leg and in spaced

2

relation with the first rear leg. The step stool comprises a platform having a length at least 1.5 times the length of the first step. The platform rotatably attached to the first front leg and the second front leg above the first step.

5 The present invention pertains to a method for using a step stool. The method comprises the steps of placing the step stool in a position so a user can climb on the step stool. There is the step of applying a cantilever load to the step stool while in the open position causing a first right leg to press against a rib which extends outwardly from a first side of a first step adjacent a first boss of the first side and in alignment with a first front leg of the step stool when the first and second front legs and first and second rear legs of the step stool are in an open position where they form a generally upside down V shape.

BRIEF DESCRIPTION OF THE SEVERAL VIEWS OF THE DRAWING

20 FIG. 1 is a perspective view of a stepstool of the present invention.

FIG. 2 is a side view of the stepstool.

FIG. 3 is a front view of the stepstool.

25 FIG. 4 is a side view of a second embodiment of the stepstool with a second step.

FIG. 5 is a front view of the second embodiment of the stepstool.

FIG. 6 is a front view of a portion of the platform.

FIG. 7 is a side view of the platform.

30 FIG. 8 is a front view of the platform.

FIG. 9 is an underneath perspective view of the step stool in an open position.

DETAILED DESCRIPTION OF THE INVENTION

35 Referring now to the drawings wherein like reference numerals refer to similar or identical parts throughout the several views, and more specifically to FIGS. 1-9 thereof, 40 there is shown a step stool 10. The step stool 10 comprises a first front leg 12. The step stool 10 comprises a second front leg 14 in parallel and spaced relation with the first front leg 12. The step stool 10 comprises a first step 16 having a length rotatably attached to the first front leg 12 and the 45 second front leg 14, a top 24 and a perimeter 26 about the top 24. The perimeter 26 having a first side 28 which extends down from the top 24. The first step 16 having a first boss 30 that extends outward from the first side 28 through which a first fastener 32 extends to attach the first front leg 12 to the first step 16. The first step 16 having a rib 34 which 50 extends outwards from the first side 28 adjacent the first boss 30 and in alignment with the first front leg 12 when the first and second front legs 12, 14 and first and second rear legs 18, 20 are in an open position where they form a generally upside down V shape. The rib 34 providing support to the first front leg 12 when a cantilever type force is applied to the stepladder. The step stool 10 comprises a first rear leg 18 hingedly attached to the first front leg. The step stool 10 comprises a second rear leg 20 hingedly attached to the second front leg 14 and in spaced relation with the first rear leg 18. The step stool 10 comprises a platform 22 having a length at least 1.5 times the length of the first step 16. The platform 22 is rotatably attached to the first front leg 12 and the second front leg 14 above the first step 16.

55 60 65 66 The rib 34 may contact the first front leg 12 when the first front leg 12 is in the open position. The rib 34 may extend at an angle across the first side 28 which corresponds to an

angle that the first front leg **12** forms with the first side **28**. The rib **34** may extend from the boss.

The step stool **10** may include a first link **36** which attaches to the first side **28** of the first step **16** and the platform **22** and a second link **38** which attaches to the platform **22** and the first step **16**. The first step **16** may hang from the platform **22** by the first and second links **36, 38**.

The stepladder may include a third link **40** which extends from the platform **22** to the first rear leg **18**. The third link **40** and the first link **36** are attached to the platform **22** at a same location.

The single rib **34** that extends down from the boss and out from the perimeter **26** of either front side of the first step **16**, strengthens the corresponding leg from a cantilever load. The cantilever load is essentially a load on the front legs similar to someone grabbing the bottom of the front legs and trying to squeeze them together.

The single rib **34**, which extends down from the boss and out from the perimeter **26** is positioned to align linearly with the front leg the rib **34** is supporting when the step stool **10** is in an open use position. By the single rib **34** extending out from the perimeter **26** and down from the boss along the inside of the leg which it is supporting, the rib **34** provides a greater surface area through which any force or load on the leg is distributed to the first step **16**. In addition, the single rib **34** by extending down from the boss effectively moves the bending or hinge point of the leg down, thus shortening the part of the leg that would otherwise bend, which effectively makes the leg stronger. This effectively shortens the bending moment regarding the leg. In this way, the platform **22** through the single rib **34** effectively supports the leg against such a cantilever load.

As shown in FIG. 1, the first front leg **12** and the second front leg **14** may be one continuous piece that forms a U shape with the top **42** of the U shape disposed above the platform **22**. The top **42** of the U shape may serve as a handle to a user standing on the platform **22**. At the middle of the top **42** of the U shape may be a grip **44** to further facilitate a user standing on the platform **22** better holding onto the top **42** of the U shape as a handle. A first hinge **64** rotatably attaches the first front and rear legs together, and a second hinge **66** rotatably attaches the second front and rear legs together.

Connected to the first rear leg **18** and the second rear leg **20** may be a crossbar **46** to provide additional stability to the stepladder tent when in the open position. At the bottom of each leg may be attached a molded rubber foot **48** that has a hole in it to receive the bottom of each leg. The rubber feet **48** serve to add more friction and thus more resistance to the stepladder moving, and thus more stability, when the stepladder **10** is in the open position. A strut **60** attaches to the first and second rear legs. The rear of the platform **22** rests against the strut **60**, and is supported by the strut **60** when the step stool **10** is in the open position.

As shown in FIGS. 4 and 5, the stepladder **10**, in a second embodiment, may have a second step **50** disposed between the first step **16** in the platform **22**, to allow the stepladder **10** to be larger and for the platform to be positioned higher off the ground and in the first embodiment shown in FIGS. 3 and 4. In the second embodiment, the first link **36** extends from the platform **22** down to the first step **16** and also attaches to the first side **28** of the second step **50**. The second step **50** is also rotatably fixed to the first and second front legs so when the stepladder **10** is moved into the folded position, the second step **50** also moves up, like the first step **16** as the first link **36** moves into the folded position, guiding the first and second steps to which it is attached to the closed position. In

all other ways, the second embodiment is configured and operates like the first embodiment.

The first step **16** is rectangular in shape. There is the first side **28**, and an opposing second side **54** parallel and spaced in relation with the first side **28**, a front side **56** that extends perpendicularly from and between the first side **28** and the second side **54**, and a rear side **58** that extends perpendicularly from and between the first side **28** and the second side **54** and in parallel and spaced relation with the front side **56**. The first, second, front and rear sides extend down from the perimeter **26**.

As shown in FIG. 7, on the first side **28**, there may be a second boss **52** which receives a fastener that extends through the bottom of the first link **36**. The top of the first link **36** and the front of the third link **42** rotatably fix or attach to the platform **22**. It should be noted that the configuration and operation of a second side **54** of the first step **16** and the platform **22** is identical to the first side **28** of the first step **16** and the platform **22**. The bottom of the first step **16** and the platform may be formed with buttressing **62**, for instance in a cross-hatching pattern which form a plurality of boxes

The present invention pertains to a method for using a step stool **10**. The method comprises the steps of placing the step stool **10** in a position so a user can climb on the step stool **10**. There is the step of applying a cantilever load to the step stool **10** while in the open position causing a first right leg to press against a rib **34** which extends outwardly from a first side **28** of a first step **16** adjacent a first boss **30** of the first side **28** and in alignment with a first front leg **12** of the step stool **10** when the first and second front legs **12, 14** and first and second rear legs **18, 20** of the step stool **10** are in an open position where they form a generally upside down V shape.

Examples of similar existing step stools to which the described rib **34** herein can be added are Werner step stool model S323PR and S322PR. The legs can be steel or aluminum tubes. The step stool **10** is able to support at least 250 lbs. of load. In a standard molding process, the rib **14** is formed with the first step **16** of the same plastic material so the rib **14** and first step **16** and first boss are all formed at the same time as one continuous single piece.

Although the invention has been described in detail in the foregoing embodiments for the purpose of illustration, it is to be understood that such detail is solely for that purpose and that variations can be made therein by those skilled in the art without departing from the spirit and scope of the invention except as it may be described by the following claims.

The invention claimed is:

1. A step stool comprising:
a first front leg;
a second front leg in parallel and spaced relation with the first front leg;
a first rear leg hingedly attached to the first front leg;
a second rear leg hingedly attached to the second front leg and in spaced relation with the first rear leg;
a first step having a length rotatably attached to the first front leg and the second front leg, a top and a perimeter about the top, the perimeter having a first side which extends down from the top, the first step having a first boss that extends outward from the first side through which a first fastener extends to attach the first front leg to the first step, the first step having a rib which extends outwards from the first side adjacent the first boss and in alignment with the first front leg when the first and second front legs and first and second rear legs are in an open position where they form a generally upside

5

down V shape, the first step and the first boss and the first rib being one continuous piece of plastic, the first boss and the rib disposed between the first step and an inside of the first front leg, the rib which extends down from the boss and out from the perimeter is positioned to align linearly with the first front leg that the rib is supporting when the step stool is in an open use position, by the rib extending out from the perimeter and down from the boss along the inside of the first front leg which the rib is supporting, the rib provides a greater surface area through which any force or load on the first front leg is distributed to the first step, and in addition, the rib by extending down from the boss effectively moves a bending or hinge point of the first front leg down, thus shortening that part of the first front leg that would otherwise bend, which effectively makes the first front leg stronger; and

6

a platform having a length at least 1.5 times the length of the first step, the platform rotatably attached to the first front leg and the second front leg above the first step.

2. The step stool of claim 1 wherein the rib contacts the first front leg when the first front leg is in the open position.

3. The step stool of claim 2 wherein the rib extends at an angle across the first side corresponding to an angle that the first front leg forms with the first side when in the open position.

10 4. The step stool of claim 3 including a first link which attaches to the first side of the platform and the step and a second link which attaches to the platform and the step.

15 5. The step stool of claim 4 including a third link which extends from the first side of the platform to the first rear leg, the third link and the first link attached to the platform at a same location.
